FOIL FEEDING AND EMBOSsing MECHa-
NISM FOR BOTTLE CAPPING AND LIKE
MACHINESNelson Vincent Burdin, Coventry, England, as-
signor to Scotts Engineering (Newport) Lim-
ited, Newport, EnglandApplication February 28, 1949, Serial No. 78,693
In Great Britain May 3, 1948

3 Claims. (Cl. 226—80)

1

The present invention relates to improvements connected with foil feeding and embossing mechanism for bottle capping and like machines of the type in which strip foil is fed into a capping head, and has for its object to provide a feeding head adapted to perform a dual function of feeding the strip foil and embossing same.

In the accompanying drawings,

Figure 1 is a sectional elevation of a bottle capping machine embodying foil feeding mechanism according to this invention.

Figure 2 is a plan view on an enlarged scale of the foil feeding mechanism and adjacent parts of the machine.

Figure 3 is a section on the line 3—3 of Figure 2.

Figure 4 is a section on the line 4—4 of Figure 3.

Figure 5 is an elevation of an adjustment member per se for the drive to the feeding head, and

Figures 6 and 7 are elevations on a further enlarged scale of cams employed to operate the feeding heads.

Referring to Figures 1 and 2 the body part comprises a block 8 which is slidably arranged with respect to the capping head 9 so that this block 8 may be reciprocated towards and away from the capping head 9 in a manner hereafter described.

The said block 8 is provided with a slot 10 adapted to receive the strip foil 11 and is mounted on a guideway 12 at one end, whilst a shaft 13 adapted for axial movement only, is secured to substantially the centre of the block 8, said shaft 13 taking a bearing in the machine frame 14 so as to support and be instrumental in imparting the required sliding motion to the aforesaid block 8.

The beforementioned slot 10, which is aligned with the capping head 9, forms two jaws, the lower one 15 of which carries a die 16 and the upper one 17 which carries a plunger 18, which plunger 18 is preferably provided with a leather or other pad 19 at its lower end adapted to bear against the die 16 when the plunger 18 is moved in a downward direction. The upper end of the plunger 18 is engaged by a lever 20 pivoted at its centre about a pin 21 on the upper side of the block 8, whilst the other end of the lever 20, engages the upper end of a rack 22 vertically disposed in the block 8, in a similar manner to the aforesaid plunger 18, but at the other end of said block 8.

The toothed portion 23 of the rack 22 engages

55

to the block 8, and at the other end to the ma-

2

a pinion 24 carried in said block 8, said pinion 24 being slidably mounted on a fixed driving shaft 25 passing through said block 8, arranged parallel with the guideway 12 and supporting and operating shaft 13 for said block 8. As shown the portion of the pinion driving shaft 25 which passes through the block 8 is of non-circular shape in cross section, and passes through a member 26 having a corresponding hole 27 therein (Figures 4 and 5), said member 26 being secured so as to be adjustable in an angular manner to an extension 28 of said pinion 24, so that angular adjustment of the pinion 24 with respect to its driving shaft 25 can be obtained.

10 The driving shaft 25 is journaled in the machine frame 14 at its other end and carries at this end a pinion 29 which is engaged by a rack 30 carried in the machine frame 14, the lower end of said rack 30 being adapted to follow a suitable driving cam 31 mounted on the shaft 43, which is driven by the worm gear 44. The rack 30 is preferably urged into engagement with the cam 31 by a spring 33. The profile of this driving cam 31 is such that an initial load is applied 15 to the embossing plunger 18 through the medium of the beforementioned rack and pinion mechanism sufficient to emboss the portion of strip foil 11 disposed within the slot 10. After the embossing has been effected the load on the plunger 18 is reduced to an extent just sufficient 20 to permit the plunger 18 and die 16 to grip the strip foil 11 for feeding purposes when a sliding motion is applied to the block 8 as hereinafter explained. Thus by reducing the load on the embossing plunger 18 in this way, the load on the driving mechanism is reduced and consequently the power required to operate the machine is lessened.

25 In order to impart a sliding motion to the block 8 the aforesaid shaft 13 fixed to same, has connected at its other end a suitable linkage 32, which linkage 32 is connected to an arm 33 mounted on a shaft 34 carried by the machine frame 14, said shaft also carrying a pinion 35. This pinion 35 is engaged by a rack 36, which rack 36 at its lower end, follows a further driving cam 37 mounted on the shaft 43 so that a rotary motion is imparted to the said arm 33, which by means of the said linkage 32 imparts a reciprocatory motion to the said slideable shaft 13 secured to the block 8. This reciprocatory motion is positive in one direction, and in order to effect the return motion, a tension spring 38 is provided which is secured at one end 30 to the block 8, and at the other end to the ma-

chine frame 14. Thus the block 8 is moved in one direction by the shaft 13 fixed thereto, by means of the rack 36 and pinion 35, arm 33 and connecting linkage 32, and in the opposite direction by the return spring 38.

With reference to Figure 6 a suitable cam 31 is shown which is for use in operating the embossing plunger 18, the embossing taking place when the lower end of the rack 30 bears against the portion 39 of the cam 31.

After the embossing operation further movement of the cam 31 causes the lower end of the rack 30 to bear against the portion 40 of the surface of the cam 31 to reduce the pressure of the plunger 18 on the embossed portion 15 of the foil 11, but retaining sufficient pressure thereon to grip same as the block 8 moves towards the capping head 9 and thus effect the feeding of the foil to the capping head 9 for the capping operation.

The cam 37 shown in Figure 7, which controls the movement of the block 8 with respect to the capping head 9 features a rising portion 41 on the periphery thereof to operate the rack and pinion mechanism 36, 35, arm 33, linkage 32 and 20 slideable shaft 13 to move the block 8 relatively quickly away from the capping head 9. Whilst the gradual fall 42 of the periphery of said cam permits of the spring 38 drawing the block 8 relatively slowly towards the capping head 9. In this way the block 8 is moved quickly away from the capping head 9 but returns slowly to the latter thus slowly feeding the foil to the capping head and preventing overrun of the foil spool 39.

I claim:

1. Improvements in bottle capping and like machines comprising in combination, a capping head, a body part slidably mounted in respect to said capping head and in alignment therewith through which foil for forming the caps is adapted to pass, an embossing die mounted in said body part, a plunger mounted in said body part adapted to co-operate with said embossing die to emboss the foil, a rotary cam for controlling the embossing of the foil and maintaining said plunger and die in gripping relation with the foil after embossing over a pre-determined period, a reciprocating rack operated by said cam, a rotary shaft operated by said rack, a pinion 35

mounted on said shaft, means operated by said pinion for effecting the reciprocation of the plunger in the body part and a cam operated linkage which is adapted to reciprocate the body part to feed the foil to the capping head.

5 2. In foil feeding and embossing mechanism for bottle capping and like machine according to claim 1, means for angularly adjusting the pinion on the shaft for effecting an adjustment of 10 the timing of the embossing plunger in relation to the rotary cam.

3. In foil feeding and embossing mechanism for bottle capping and like machine, the combination of a machine frame, a capping head mounted on said frame, a body part slidably mounted on the frame in respect to the capping head and in alignment therewith, an embossing die mounted in said body part, an embossing plunger slidably mounted in said body part, a cam shaft, a cam member on said cam shaft, a toothed rack reciprocated by said cam member, a pinion carried by a shaft adapted to engage said toothed rack, a second pinion mounted on said shaft engaging a rack in the body member, a pivoted lever engaging said rack and the embossing plunger to operate same and retain said plunger and die in gripping relation with the foil after embossing over a predetermined period, a second cam member on said cam shaft, a slideable toothed rack operated by said second cam member which is adapted to control linkage to reciprocate the body member to and from the capping head to feed the embossed foil to said capping head.

35 NELSON VINCENT BURDIN.
